UNITED STATES PATENT OFFICE.

PETER BOYD, OF BEAVER, AND AUGUSTUS M. SAUNDERS, OF MCKEESPORT, PENNSYLVANIA, ASSIGNORS TO NATIONAL TUBE COMPANY, OF PITTSBURGH, PENNSYLVANIA, A CORPORATION OF NEW JERSEY.

METHOD OF FORMING COUPLING ENDS ON DRILL-TUBE SECTIONS.

1,325,073.

Specification of Letters Patent.

Patented Dec. 16, 1919.

Application filed May 25, 1918. Serial No. 236,577.

To all whom it may concern:

Be it known that we, PETER BOYD and AUGUSTUS M. SAUNDERS, citizens of the United States, residing at Beaver, Beaver county, Pennsylvania, and McKeesport, Allegheny county, Pennsylvania, respectively, have invented certain new and useful Improvements in Methods of Forming Coupling Ends on Drill-Tube Sections, of which

10 the following is a specification.

This invention relates to an improved method for forming integral coupling ends on the ends of welded or seamless tubes of the class used for core drills and shot drills. 15 Heretofore it has been customary to join the ends of such tube sections by means of detachable unions or other fittings, which in practice has been found to be more or less unsatisfactory because continued use of the 20 so-formed drill tends to loosen the parts and make it necessary to frequently repair and replace the fittings.

Heretofore it has not been possible to form integral coupling members on the ends 25 of the drill tube sections owing to the thinness of the wall of drill tubes such as are used in this art. It is obvious that this objection could not be overcome by merely utilizing tubes having very thick walls, because 30 these drills are usually very long, sometimes reaching a length of three thousand feet, and the extra weight due to the increased thickness of the wall of a drill tube of such length would make the use of such 35 tubes prohibitive, such a drill tube naturally being a great deal more expensive to manufacture and requiring greater power to operate.

By the utilization of our method we are 40 able to increase the thickness of the wall of the drill tube at the ends thereof to give sufficient metal for the formation of an integral coupling without adding materially to the weight of the tube section.

45 Our invention is illustrated by the accompanying drawings in which:—

Figure 1 and Fig. 2 are respectively a longitudinal section and an end elevation showing the uniform wall thickness and the rel-

ative diameter and wall thickness of a tube 50 before being subjected to any of the steps of our method.

Figs. 3 to 11 inclusive are longitudinal sections on any axial line of the tube illustrating the various successive steps in our 55 improved method of upsetting or thickening the tube wall at the ends of the drill tube of Figs. 1 and 2.

Fig. 12 is a longitudinal section of the male end of the drill tube after the upsetting operations have been completed to the extent shown in Fig. 11.

Fig. 13 illustrates the condition of the tube after being swaged to form a tapered end thereon in forging the male end of the 65 tube.

Fig. 14 shows the completed male end of the drill tube with a screw thread cut on the tapered end.

Fig. 15 is a section on the line 15—15 of 70 Fig. 14.

Fig. 16 is a longitudinal section of the female end of a drill tube which has been upset in a similar manner to that illustrated in Figs. 3 to 11, inclusive. 75

Fig. 17 illustrates the finished form of the female end of the drill section showing the internal threads formed therein.

Fig. 18 is a sectional view on line 18—18 of Fig. 17. 80

In carrying out our method, the end of a tube, made by the lapweld, seamless or other approved process, after first being heated, is inserted in a die having a diameter the same as that of the exterior of the tube, the 85 axes of the die and tube coinciding. The heated tube end is then subjected to endwise pressure by an upsetting press, the action of the upsetting press slightly increasing the thickness of the walls of the tube as shown 90 in Figs. 4 and 5, and the metal being displaced inwardly due to the restraining action of the surrounding outer die. The upsetting operation is repeated several times, the result, as shown in Figs. 5, 6, 7, and 8, 95 being to materially shorten the thickness in the tube wall at the end thereof by displacing the metal inwardly, the wall thickness

being increased and the length of the tube being lessened somewhat by each upsetting operation.

When sufficient thickness of the end walls of the tube has been obtained, we then remove the exterior die used for the former operations and substitute in place thereof a die A having an interior contour of substantially the shape shown in Fig. 9 in which the diameter at the end of the die is slightly greater than the outside diameter of the drill tube. We then subject the end of the tube to another series of operations which action expands the end of the tube, offsetting the thickened wall thereof outwardly as indicated in Fig. 9, whereupon we again subject the end of the tube to another series of lengthwise compressing or upsetting operations which causes the metal of the tube wall to be so displaced that it fills the enlarged cavity A' of the die as shown in Figs. 10 and 11.

After the completion of the above steps of our method the end of the tube will be formed up to the shape illustrated in Fig. 12, and we then submit the end of the tube to a swaging operation to form the tapered end B and the shoulder C thereon. A suitable tool is then employed to form the screw threads D on the tapered end C thereof which completes the male end of the drill tube.

The method of forming or upsetting the female end of the tube is substantially the same as that above described with the exception that the tapered end B is not swaged thereon, the interior threads E being cut on the inner wall of the tube to coact with the threads D on the mating end of an adjacent drill section.

We are aware that it is not generically new to perform simple upsetting operations upon tubular work, but it is our belief that such operations have never before been successfully carried to such a great extent as has been done by the method herein disclosed. We also believe that it is novel to first increase the thickness of the walls of the tube by displacing the metal inwardly and then offsetting the thickened wall as described, to form a hub on the tube.

The continual working of the metal increases its fiber strength thus making a tougher end on the drill tube at the point at which the excessive strains are usually felt in core drills and the like. With a drill tube thus formed, as the threads of the coacting coupling members become worn through continued use, the threads can be recut and the shoulder C of the hub be cut back as indicated in dotted lines in Fig. 14. Similarly the interior threads E may also be recut when they become badly worn, the walls at the end of the tube in each case be-

ing sufficiently thick to permit of several recutting operations before the tube will have to be finally discarded.

Though we have described in considerable detail the various steps in carrying out our method, it is obvious that slightly different steps may be employed or the sequence of operations somewhat changed by those skilled in the art without departing from the spirit and scope of the invention as outlined in the following claims.

We claim:

1. The method of forming hubs on tubes which consists in shortening the tube and materially increasing its wall thickness adjacent to an end of the tube in a series of small and successive upsetting operations and forcing the displaced metal radially inward in said successive upsetting operations and then further shortening the tube and increasing the wall thickness of the thickened end in a second series of small and successive operations and forcing the displaced metal radially outward in at least part of said second series of upsetting operations.

2. The method of forming hubs on tubes which consists in shortening the tube and materially increasing its wall thickness adjacent to an end of the tube in a series of small and successive upsetting operations and forcing the displaced metal radially inward in said successive upsetting operations and then further shortening the tube and increasing the wall thickness of the thickened end in a second series of small and successive operations and forcing the displaced metal radially outward in at least part of said second series of upsetting operations and then swaging the thickened tube end to further shape the hub of the tube and thereby provide a tapered end thereon.

3. The method of forming hubs on tubes which consists in shortening the tube and materially increasing its wall thickness adjacent to an end of the tube in a series of small and successive upsetting operations and forcing the displaced metal radially inward in said successive upsetting operations and then further shortening the tube and increasing the wall thickness of the thickened end in a second series of small and successive operations and forcing the displaced metal radially outward in at least part of said second series of upsetting operations and then machining the hub and cutting screw threads thereon.

4. The method of forming hubs on tubes which consists in shortening the tube and materially increasing its wall thickness adjacent to an end of the tube in a series of small and successive upsetting operations and forcing the displaced metal radially inward in said successive upsetting operations and then further shortening the tube and in-

creasing the wall thickness of the thickened end in a second series of small and successive operations and forcing the displaced metal radially outward in at least part of 5 said second series of upsetting operations and then swaging the thickened tube end to further shape the hub of the tube and there-

by provide a tapered end thereon and then machining the hub and cutting screw threads thereon.

10

In witness whereof, we have hereunto signed our names.

PETER BOYD.

AUGUSTUS M. SAUNDERS.
